UNITED STATES PATENT OFFICE.

JOHN G. HODGSON, OF MAYWOOD, ILLINOIS, ASSIGNOR TO AMERICAN CAN COMPANY, OF NEW YORK, N. Y., A CORPORATION OF NEW JERSEY.

FRICTION-TOP CAN.

SPECIFICATION forming part of Letters Patent No. 795,126, dated July 18, 1905.

Application filed December 5, 1904. Serial No. 235,464.

To all whom it may concern:

Be it known that I, JOHN G. HODGSON, a citizen of the United States, residing in Maywood, in the county of Cook and State of Illinois, have invented a new and useful Improvement 5 in Friction-Top Cans, of which the following is a specification.

My invention relates to improvements in cans of the kind or class commonly known as "friction-top" cans or cans which are designed to be opened and closed a number of times as the contents are being used and which have a top or head furnished with a friction-seat adapted to receive a friction or slightly-wedging 15 cover that is forced into the seat to tightly close the can by the tight close metal-to-metal contact of the cover with the seat in the top or head of the can. Great difficulty has heretofore been experienced in cans of this 20 kind or class in producing a liquid-tight closure or joint between the so-called "friction-top" of the can and its so-called "friction-cover," especially where the cans are filled with extremely permeable or fluid liquids, 25 like turpentine, benzin, &c.

The object of my invention is to provide a so-called "friction-top" can of a simple, efficient, durable, and economical construction which may be readily closed and sealed by 30 simply forcing the cover in place and readily opened by simply prying off the friction-cover and which at the same time may be closed liquid-tight with certainty and reliability, so that substantially none of the cans 35 will in practice prove to be defective or leaky.

My invention consists in the means I employ to practically accomplish this object or result—that is to say, it consists in a can having 40 an annular top or head furnished with the customary integral seat wall or flange for the cover, having an inwardly-projecting flange provided with an upwardly-projecting flange terminating in a rounded or curved flange 45 and constituting an elastic or spring-acting member, in combination with a friction-cover having an integral seat wall or flange tightly engaging the seat wall or flange of the can-top and provided with an inner upright wall

or flange terminating in a rounded flange or 50 wall engaging the elastic-acting flange of the can-top, whereby the can is adapted to be closed liquid-tight with certainty and reliability.

My invention also consists in the novel construction and in the novel combinations of parts and devices herein shown or described.

In the accompanying drawings, forming a part of this specification, Figure 1 is a central vertical section of a friction-top can embodying my invention. Fig. 2 is a top or plan view. Fig. 3 is an enlarged detail vertical section, and Fig. 4 is a plan view with the friction-cover removed.

In said drawings, A represents the can-body, and C its bottom head, secured thereto by a soldered or other seam c.

B is the annular top, secured to the can-body by a soldered or other seam a. The annular top B has a marginal flange b for securing the same to the can-body and a raised bead or shoulder b' to serve as a fulcrum in prying off the friction-cover D. The top B has an integral depending seat wall or flange b² tightly engaging the corresponding seat wall 75 or flange d of the friction-cover D, these interengaging seat-walls b² d being preferably slightly wedging or tapering and the seat-wall d of the cover being slightly larger than the seat-wall b² of the can-top to insure a firm 80 and tight gripping or anchorage of the two together when the cover D is forcibly pressed or driven home in the can-top B. The annular can-top B also has an inwardly-projecting flange b³ and an upwardly-projecting flange 85 b⁴, terminating in a curved or rounded elastic or spring acting flange or member b⁵. The annular walls or flanges b² and b⁴ and the inwardly-projecting flange b³ together form an annular recess or channel B' in the can-top. 90

The friction-cover D is provided with marginal folded flanges d' at its rim to strengthen the same and form a shoulder for prying off the cover. The friction-cover D has in addition to the friction seat wall or flange d an inwardly-projecting flange d² and an upwardly-projecting flange d³ and a curved or rounded annular seat flange or wall d⁴, which

engages and forms a seat for the elastic or spring acting flange b^5 of the top B. The flanges d , d^2 , and d^3 of the friction-cover D form a raised annular rib on the under side 5 of the friction-cover which fits in the annular recess or groove B' of the friction-top, and as this annular rib on the cover is substantially rigid and unyielding, while the inner upright wall d^4 of the annular recess or channel B' of 10 the can-top is elastic and free to spring slightly inward as the cover D is forced snugly home, it produces an elastic or spring action between the interengaging members b^4 d^2 and b^5 d^4 , and thus secures a liquid-tight closure with 15 certainty and reliability. As the spring-pressure of the elastic flanges b^4 b^5 against the co-acting cover-walls d^2 and d^4 is chiefly in a horizontal direction, this spring-valve-acting pressure does not materially tend to press the 20 cover off or upward, and the tight wedging friction-grip between the upright walls b d^2 and b^2 d^4 effectually counteract any upward component of pressure of the spring-acting member b^5 against its rounded seat d^4 , so that 25 the cover remains securely anchored on the can. When the friction-cover is pressed home on the top to close the same, there is a free space between the inwardly-projecting flange d^2 of the cover and the corresponding 30 inwardly-projecting flange b^3 of the top B, so that these flanges will not operate as stops to arrest the downward movement of the cover, and thus prevent the necessary close tight gripping or anchorage of the upright friction 35 seat-walls b^2 d of the top cover.

I claim—

1. In a friction-top can, the combination with a top having a friction seat-wall provided with an inwardly-projecting flange and a reverse upwardly-projecting flange terminating 40 in a curved spring-acting member, of a friction-cover having an upright friction seat-

wall, an inwardly-projecting flange and an upwardly-projecting flange having a rounded seat member, substantially as specified. 45

2. In a friction-top can, the combination with a top having a friction seat-wall provided with an inwardly-projecting flange and a reverse upwardly-projecting flange terminating in a curved spring-acting member, of a friction-cover having an upright friction seat-wall, an inwardly-projecting flange and an upwardly-projecting flange having a rounded seat member, said can-top having a marginal raised rim to serve as a fulcrum in prying off 50 the cover, substantially as specified. 55

3. In a friction-top can, the combination with a top having a friction seat-wall provided with an inwardly-projecting flange and a reverse upwardly-projecting flange terminating in a curved spring-acting member, of a friction-cover having an upright friction seat-wall, an inwardly-projecting flange and an upwardly-projecting flange having a rounded seat member, said can-top having a marginal raised rim to serve as a fulcrum in prying off 60 the cover, and said friction-cover having a folded marginal rim, substantially as specified. 65

4. In a friction-top can, the combination with a top having a sunken recess, the outer upright wall of said recess serving as a friction-seat, of a friction-cover having a corresponding annular channel, the upright walls of which engage the upright walls of the annular channel in the top, the inner upright wall of the top having a curved spring-acting member, and the friction-cover having a corresponding annular seat-wall, substantially as specified. 70 75

JOHN G. HODGSON.
